Primary Examiner — Darlington Ly

(57) **CLAIM**

The ornamental design for an electric bicycle as shown and described.

DESCRIPTION

The patent or application file contains at least one drawing executed in color. Copies of this patent or patent application publication with color drawing(s) will be provided by the Office upon request and payment of the necessary fee.

3.-4. Electric bicycle

3.1 is a front view of an electric bicycle showing our new design in accordance to a first embodiment;

3.2 is a rear view thereof;

3.3 is a right side view thereof;

3.4 is a left side view thereof;

3.5 is a top view thereof;

3.6 is a bottom view thereof;

3.7 is a front-left side perspective view thereof; and

3.8 is a rear-right side perspective view thereof.

4.1 is a front view of an electric bicycle showing our new design in accordance to a second embodiment;

4.2 is a rear view thereof;

4.3 is a right side view thereof;

4.4 is a left side view thereof;

4.5 is a top view thereof;

4.6 is a bottom view thereof;

4.7 is a front-left side perspective view thereof; and

4.8 is a rear-right side perspective view thereof.
